EDWARD A. CUNNIFF, OF WALTHAM, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed April 23, 1926. Serial No. 104,190.

This invention relates to feeler mechanisms for looms, whereby the filling in the shuttle is changed from time to time while the loom continues to run.

In feeler mechanism of the penetrating and impinging type, it is now the ordinary practice to provide a penetrating feeler member which will penetrate or enter the filling on each detecting beat and permit the impinging feeler member to take the full frontward impact of the filling to move the feeler slide on which the feeler members are usually mounted, towards the front of the loom. The present invention is more particularly concerned with feeler mechanisms of the penetrating and impinging type, and has for its object to provide an improved construction whereby feeler mechanisms of the caliper type now employed, may be readily converted into the penetrating and impinging type.

Another important feature of the invention consists in providing a penetrating and impinging type of feeler wherein the penetrating member shall be fixed to the feeler slide and the impinging member shall be slidably mounted on the feeler slide to take the first impact of the filling and then be moved frontwardly to effect movement of the actuator from a normally operative to an inoperative position on detecting beats when a working supply of filling is present in the shuttle. In accordance with the present invention, the first impact of the filling upon the impinging member causes the latter to move the actuator into its inoperative position when a working supply of filling is present in the shuttle, and after such inoperative positioning of the actuator, the present invention provides that the full impact of the oncoming filling shall be sustained by a member fixed to the feeler slide.

Other features of the invention reside in details of construction whereby the general objects of the present invention are effectively carried into operation.

The invention and new features thereof will best be made clear from the following description and the accompanying drawings of one good form thereof.

In the drawings:

Fig. 1 is a perspective view of the feeler side of a loom containing the present invention;

Fig. 2 is an enlarged side elevation of the feeler mechanism containing the present invention, some of the parts being broken away;

Fig. 3 is a plan view showing the relation of parts when the shuttle contains a working supply of filling on a detecting beat;

Fig. 4 is an enlarged detail broken away, showing the relation of parts when the filling is substantially exhausted on a detecting beat;

Fig. 5 is a detached detail showing the construction of the impinging member of the feeler; and

Fig. 6 is a detail sectional view, showing more particularly the impinging member and its overlying cover plate.

The present invention is designed for association with filling replenishing devices, but since the details of such devices form no essential part of the present invention, the replenishing mechanism is not herein illustrated.

The loom frame 1 may be of usual construction and rising from the usual transverse or rock shaft (not shown) is an arm 2 to which is pivotally connected at 3 the arm 4, the rear end portion of which is adapted at times to be engaged by an operating member 5 connected to the cam follower. Underlying the arm 4 is the lifter arm 6 pivotally mounted at 7 and having an arm 8 associated therewith, which is caused at times to move up the inclined or cam surface 9 to insure replenishment of filling. The mechanism thus far described is old in the art and may be of usual type.

The shipper stand 10 carries a bracket 11 on which is mounted the feeler stand 12. In the present instance the feeler stand is adjustably secured in place on the bracket 11 by means of the bolts 13 which pass through an opening 14 in the feeler stand or flanges extending laterally therefrom.

Mounted for sliding movement towards and from the front of the loom is the feeler slide 15 which is normally pressed rearwardly by the usual spring 16.

Pivottally supported upon the feeler slide 15 at 17 is the actuator 18, the frontwardly extending arm 19 of which is normally positioned by gravity of the arm 19 for engagement with the transmitter or arm 8 as the feeler slide is moved frontwardly, the effect

being that upon such engagement filling replenishment will be initiated.

Extending downwardly from the actuator 18 is a heel 20 adapted to be struck by a bunter carried by the impinging feeler member, as will presently appear, and thereby move the actuator from its lowered or operative position to its upper or inoperative position when a working supply of filling is present in the shuttle on a detecting beat.

The lav carries the usual shuttle box 21 in which the shuttle 22 is received and the front walls of the shuttle and shuttle box are provided with openings 24 which register when the shuttle is in proper position in the shuttle box, the construction being such that on detecting beats, the feeler (presently to be described) will enter the shuttle and detect the condition of the filling.

The feeler slide 15 has at its rear end portion a penetrating feeler member 25 which is located at one side of the feeler slide and is adapted to enter or penetrate the filling when, on a detecting beat, a working supply is present in the shuttle.

Mounted upon the feeler slide 15 is an impinging feeler member 26, best shown in Fig. 5, which is extended laterally at its rear end portion, as at 27, to provide a substantial extent of filling engaging surface. The impinging feeler member 26 is mounted on the feeler slide 15 at one side of the penetrating feeler member 25, as indicated in Figs. 1 and 3.

The impinging feeler member 26 is formed as a plate which is mounted for sliding movement in guideways 28 formed on the feeler slide. The forwardly extending portion of the impinging feeler member 26 is formed with a slot 29 and adjustably connected to the impinging feeler member 26 is the bunter 30 having an end portion 31 adapted to engage the heel 20 of the actuator. The bunter 30 is formed as a plate and is also provided with an elongated slot 32 through which passes the bolt 33 which is screw threaded at its lower end to receive a nut 34, whereby the impinging member 26 and its bunter 30 may be adjustably associated to effect movement of the actuator into its inoperative position when the impinging member 26 is moved forwardly by a working supply of filling on a detecting beat.

In accordance with one feature of the present invention, the impinging member 26 is utilized to effect movement of the actuator from its normally operative to an inoperative position when the impinging member is pushed forwardly by a working supply of filling on a detecting beat, and upon the completion of such inoperative position of the actuator, the forward push of the filling is sustained by the feeler slide

to effect forward movement thereof, and thus relieve the impinging member from its stress.

In the present instance of the invention, the impinging feeler member 26 is confined to its guideways on the feeler slide by means of a cover plate 35 which may be secured by pins or bolts 36 to the rear end portion of the feeler slide. The rear end portion 37 of the cover plate 35 extends rearwardly beyond the rear end of the feeler slide 15, with the result that when a working supply of filling is present in the shuttle on a detecting beat and the impinging member 26 is moved forwardly to inoperatively position the actuator, the forward stress of the oncoming filling is taken by the rear end portion 37 of the cover plate, the result being that the impinging member 26 by its sliding movement on the feeler slide serves to inoperatively position the actuator by the forward impact of the filling and upon the completion of such inoperative position of the actuator, the feeler slide itself through the rear edge portion 37 of the cover plate sustains the forward pressure of the filling which serves to move the feeler slide and the actuator forwardly.

Inasmuch as the function of the impinging member 26 is confined to inoperatively positioning the actuator, it is important that the position of the bunter 30 on the impinging member shall be accurately adjusted to effect such movement of the actuator and thereafter permit the rear end portion 37 of the cover plate to take the full impact of the surface within the shuttle to effect forward movement of the feeler as a whole.

The rearward position of the impinging member 26 should be such that its filling engaging face 27 may extend sufficiently far rearward of the rear end of the cover plate 37 to permit the rear end of the cover plate 37 to engage the filling when the impinging member has effected its purpose which, as above stated, is to inoperatively position the actuator when a working supply of filling is present on a detecting beat. In the present instance of the invention, the rearward movement of the impinging feeler member 26 is limited by a stop which may be adjusted to different positions to accord with the range of movement required of the impinging member, and in the present instance, such stop is formed by a washer 38 interposed between the head of the bolt 33 and the top surface of the bunter 30 and a cooperating stop formed at the front edge portion 39 of the cover plate 35.

From the construction described it will be apparent at once that the position of the bunter 30 may be adjusted by loosening the bolt 33, without at the same time disturbing the relation of the cooperating stops 38 and

39. Similarly, the position of the stops which determine the rearward position of the impinging member may likewise be adjusted without at the same time disturbing the relation between the impinging member 5 and the bunter 30.

When a working supply of filling is present in the shuttle on a detecting beat, as indicated in Figs. 2 and 3, the penetrating member 25 will sink into the filling and thereby permit the oncoming filling to engage the broad face 27 of the impinging member, and move it frontwardly to an extent preferably sufficient only to move the 15 actuator from its operative to its inoperative position, and thereupon the filling engages the rear end portion 37 of the cover plate 35 and pushes the feeler slide frontwardly, thereby taking the stress of the forward pressure. When, however, the filling is substantially exhausted on a detecting beat, as indicated in Fig. 4, the penetrating feeler member 25 will meet the more dense surface 20 of the filling carrier or bobbin and the impinging feeler member 26 will not be moved frontwardly relative to the feeler slide, with the result that the actuator will remain in operative position and on forward movement of the feeler slide will effect replenishment 25 of filling.

What is claimed is:

1. In a feeler mechanism for looms, the combination of a feeler slide having a penetrating member fixed thereto, an impinging member of substantial extent at one side of the penetrating member having a slotted body portion mounted for sliding movement in the feeler slide, an adjustable stop mounted on the slotted body of the impinging member for varying the rearward position of the impinging member relative to the feeler slide, an actuator pivotally mounted on the feeler slide, and an adjustable bunter mounted on the slotted body of the impinging member for moving the actuator.

2. In a feeler mechanism for looms, the combination of a feeler slide having a fixed penetrating member, an impinging member mounted for sliding movement on the feeler slide, a cover plate secured to the feeler slide and overlying the impinging member and extending rearwardly beyond the rear end of the feeler slide to engage the filling on a detecting beat when the impinging member has been moved frontwardly by a working supply of filling, an actuator adapted to be moved by the impinging member from the operative position when the impinging member is moved frontwardly on the feeler slide to permit the rear of the cover plate to sustain the forward pressure of the filling and cause forward movement of the feeler slide.

3. In a feeler mechanism for looms, the

combination of a feeler slide having a fixed 65 penetrating feeler member, an impinging feeler member mounted for sliding movement on the feeler slide, an actuator adapted to be moved by the impinging member from its operative position, and a fixed plate on 70 the feeler slide extending rearwardly to a position between the rear end of the penetrating and the rear end of the impinging members to receive the forward pressure of a 75 surface within the shuttle and relieve the impinging member and actuator from said pressure when the impinging member has been moved forwardly on the feeler slide sufficiently to move the actuator to the desired position.

4. In a feeler mechanism for looms, the combination of a feeler slide having a fixed penetrating member, an impinging feeler member comprising a plate having an impinging surface extending a substantial distance at one side of the penetrating member and mounted for sliding movement on the feeler slide, a bunter adjustably mounted on the impinging member, a normally operatively positioned actuator which is moved to an inoperative position when the impinging member is moved on the feeler slide by a working supply of filling, and a cover plate overlying the impinging member and extending rearwardly to sustain the forward pressure of the filling and relieve the impinging member after it has inoperatively positioned the actuator.

5. In a feeler mechanism for looms, the combination of a feeler slide having a fixed 100 penetrating feeler member, an impinging feeler mounted for sliding movement on the feeler slide and comprising a slotted plate, a bunter having a slot, a bolt for securing the bunter in adjusted position on the impinging member, and a cover plate overlying the impinging member and acting as a stop for limiting rearward movement of the impinging member.

6. In a feeler mechanism for looms, the combination of a feeler slide having a fixed penetrating feeler member, an impinging feeler member mounted for sliding movement on the feeler slide, a bunter carried by the impinging member, an actuator pivotally mounted on the feeler slide and having a forwardly extending arm acting by gravity to maintain the actuator normally in operative position, and a downwardly extending heel carried by the actuator for engagement by the bunter of the impinging member, and an adjustable stop for limiting the movement of the impinging member under the gravity control of the actuator.

In testimony whereof, I have signed my 125 name to this specification.

EDWARD A. CUNNIF
